UNITED STATES PATENT OFFICE.

PETER COOPER HEWITT, OF NEW YORK, N. Y., ASSIGNOR TO COOPER HEWITT ELECTRIC COMPANY, A CORPORATION OF NEW YORK.

APPARATUS FOR THE ELECTRICAL PRODUCTION OF LIGHT.

1,030,178.

Specification of Letters Patent. Patented June 18, 1912.

Application filed April 11, 1898. Serial No. 677,199.

To all whom it may concern:

Be it known that I, PETER COOPER HEWITT, of the city of New York, borough of Manhattan, in the county and State of New York, have invented certain new and useful Improvements in Apparatus for the Electrical Production of Light, of which the following is a full, clear, and exact description.

The object of my invention is to provide a new and useful means of producing light by electricity, whereby a light of high illuminating power is produced, and the intensity and color of the light may be varied.

I have discovered that certain vapors of specific density and physical condition have the property of becoming intensely light radiant when an electric current is passed through them. Such a vapor is the vapor of mercury, sodium, iodin and other metals, each producing a light with colors peculiar to itself. The light giving quality depends chiefly on the density of the vapor, as well as the material, it being most intense at the point of saturation, or boiling point of the metal, the light giving quality being somewhat proportioned to the density. Besides simple metallic vapors, other gases have this property to a certain extent, but most of them are objectionable on account of the temperature necessary, and also on account of the electrical resistance at the point where their vapor is in the physical state, which allows them to be light radiant. For these reasons their use in many cases is impracticable. In the case of mercury, which is a fair example of a metal volatilizing at a practical temperature, the vapor is inclosed or formed in a tube whose ends are turned down so as to hold a globule of mercury, into which are led wires for conducting the electrical current, which wires may be submerged in the volatilizable material or not, as desired. In case the wire or electrode projects through the material to be volatilized, the wire becomes heated on the discharge of an electric current, which in turn heats the material to be volatilized and volatilizes it, filling the tube with its vapor, if the tube is not already of such a temperature that it is not sufficiently full of vapor. It is well known that a wire leading into an attenuated atmosphere becomes heated, although the same sized wire will conduct the circuit under ordinary conditions without heating.

55 In the case where the material to be volatil-

ized constitutes the electrode, the current heats the electrode direct, producing the same effect. A tube may be constructed containing an exact amount of vapor (or material to produce the vapor) necessary to produce this intense light electrically, in which case the exact degree of vapor density and physical condition can be produced which is most advantageous. The electrodes must be made of such size as not to be deteriorated by the electrical discharge. The light action of these tubes is intermittent and the electric current impulses or oscillations can be made with the frequency desired, and so rapid as to require a most delicate instrument to detect that the light is not continuous. A tube in the form described, one quarter of an inch in diameter, one foot in length will produce a light too brilliant to look at, the light being more than a hundred candle power. The quantity of light may be varied by the current used, from great brilliancy to the bare luminosity of ordinary vacuum tubes or Geisler tubes. This tube is practically indestructible, having nothing to ruin or destroy, operating at somewhere about a temperature of 300° C., if mercury is used. In the case where other metals or materials are used, my tubes operate at the temperature a little above the boiling point or thereabout, of the substance in a vacuum. It is advisable to use a substance which volatilizes at ordinary temperatures as near as possible, for economy. The metal rubidium gives a deeper red light than any other, and I prefer to use this metal or a metal having a deep red band in the spectrum; or a proportion of this metal to obtain a deeper red color in my tubes. Potassium, also lithium give fair results, the temperatures being higher. In practice a more agreeable light will be produced by the judicious use of two or more tubes, each containing different vapors.

In order to more fully explain my invention, reference is had to the accompanying drawing forming a part of the specification, in which similar characters of reference indicate corresponding parts in all the figures.

Figure 1 is a side elevation of one form of a plant for producing light; Fig. 2 is a side elevation of a modified form of tube; and Fig. 3 is a longitudinal section of a straight tube having a volatilizable material at one end only.

A is an electric generator, B is a transformer, C a condenser, D D' wires, terminating in the electrodes E E', extending into the volatilizable substance F, contained in 5 the bulbs G' G² of the vacuum tube G.

The form of converter shown in Figs. 1 and 2 is shaped and arranged like an inverted letter U. The two legs of the U are shown similar and symmetrical, as are also 10 the electrode chambers, the bodies of liquid therein and the leading-in wires. From this symmetrical arrangement it results that when an alternating electromotive force is impressed first on one electrode and then on 15 the other as by the transformer B, or by condenser C, or by both together, the fluxes in both directions, find substantially the same physical and electrical conditions at their respective electrodes and the operations 20 and reactions are the same for each half wave except that the directions are reversed.

To operate my light, I use an electric current of varying voltage, having found that 25 from 500 to 5,000 volts most successful; but it can be operated at many other electrical pressures, depending on the length of the tube G desired to operate, and the quantity of light to be produced; also for the material 30 used. I place across the wires D D' leading to the tube G the condenser C which is of suitable capacity; the object of the condenser being to accumulate the electric current during the minute period of time when the 35 current is not passing through the tube G, and deliver the accumulation to the tube G during the time the tube is taking current. The condenser also aids the light giving quality of the tube. This condenser C being 40 in resonance with the tube G and with the source of current, will adjust the voltage of the current in some degree to any varying resistance that may occur in the tube. The tube itself is a condenser of certain capacity 45 under the condition that I establish, and under light giving conditions is oscillatory or intermittent, acting somewhat as a discharge for the condenser, producing waves or pulsations in the current from the condenser. The tube G is constructed with the 50 volatile electrodes E E' in the bulbs G, G², G' G², and is proportioned in size to the current to be used. The resistance of the vapor in a high degree of attenuation is 55 greater than it is when it becomes a little more dense; then becoming more dense the electrical resistance increases so that if the electrodes overheat, the vapor generated will shut off the electric current until they are 60 again sufficiently cool, but with a properly constructed tube the volatilized mercury will condense at substantially the same rate at which it is volatilized, so that the shutting off of the current does not occur except 65 through accident and in any given case may

obviously be prevented by any means which will decrease the rate of evaporation or increase the rate of condensation. At a constant pressure the electrical resistance of vapor decreases as the temperature increases. 70

In order to produce one of my tubes, I first exhaust it to a high vacuum, hot, then turn on the electric current and while the current is on, cause the absolutely pure vapor to flow through the tube, or generate in the tube and flow into the pump until it has carried away with it all the impurities existing in the tube. When this is accomplished at the required vapor density 75 (pressure and temperature), the fact becomes self-evident by the great quantity of light coming from the tube. The quantity of light is approximately proportional to the vapor density. The quantity of light is 80 under absolute control, electrically or otherwise. I have found it advantageous, even when operating tubes at almost atmospheric pressure temperature, to prevent radiation of heat to avoid the heat loss. As the vapor in the tube is very attenuated in the case of metals that volatilize above the atmospheric temperature, it may become necessary 85 in the economical use of some of them to use a starting device, to acquire the proper 90 vapor density on starting. Such a starting device may consist of applied or external heat or an increased electrical potential for the time being. I have found in the case of mercury where the tube operates at about 95 300° C. that by supplying from an outside source, the heat which otherwise would be radiated from the tube, I have a somewhat corresponding increased production of light. In fact, with the tube operating at this 100 temperature, which tube may be of the dimensions set forth in the early part of the specification, a brilliant light of especially high efficiency may be secured, even without the supplying of heat from an outside source. 105 These tubes may be made in almost any shape from spirals to straight tubes, or inverted U-shaped tubes, or U-shaped tubes; but in the case of a U-shaped tube used for volatile material I prefer to use the inverted 110 U-shaped tube, shown in Figs. 1 and 2, but in some cases the tube may be used or formed with a downwardly curved intermediate portion containing a body of mercury which may fill the cross-section of the tube, 115 so as to form a partition separating two vacuous spaces, or I may use two tubes jointed together and having a body of mercury at the point of juncture. In order to equalize the pressure within the tube, I may 120 provide the same with a reservoir G³ in communication with the interior of the tube to be filled with vapor, which, however, is not affected by the current nor rendered 125 luminous, as the current does not pass 130

through it, and hence the vapor contained therein can act as an equalizer to give the light a uniform brilliancy and steadiness.

Fig. 3 shows a straight tube with a volatile substance at the lower end, and a solid piece of iron or the like suspended in the upper enlarged end, electric wires leading to the substance and the piece of iron.

The electrical resistance of varying saturated vapors varies in a very great degree for the same density, mercury vapor being of comparatively low resistance and iodin vapor of high resistance. I prefer to use vapors of low electrical resistance as more economical and convenient.

In producing my tubes containing mercury I have found that a very small amount of oxygen or oxid of mercury in the tube increases in a marked degree the electrical resistance and impairs the light radiating quality. I have also found that the combination of two or more tubes, each giving rays of light of a different color, is advantageous.

I claim as my invention:

1. A mercury vapor lamp comprising an inverted U shaped exhausted container with an enlargement at each end partly filled with mercury constituting electrodes.
2. A mercury vapor lamp comprising an inverted U shaped exhausted container with an enlargement at each end partly filled with mercury, and also provided with a regulating chamber communicating with the interior of the main chamber cut out of the path of the current therein.
3. A vapor electric lamp having a highly exhausted chamber formed in the shape of an inverted U, having a main light giving portion of uniform diameter expanded at each end into enlargements, said enlargements being partly filled with mercury constituting electrodes and a condensing chamber centrally located along said tubular portion whereby the vapor pressure within the container is regulated.
4. The combination with a mercury vapor

lamp including a highly exhausted container having a curved tubular light giving portion, two enlargements of said tubular portions located at lower extremities in said container, and mercury electrodes at the extremities of said tubular portion, together with an electric source therefor adjusted to maintain a temperature of approximately 300 degrees centigrade in said tube whereby an efficient source of illumination is secured.

5. A mercury vapor apparatus comprising an exhausted container, suitable mercury electrodes therein and a light giving tubular portion thereof, together with means for adjusting the density of the mercury vapor therein during normal operation to the density corresponding to approximately 300 degrees centigrade, said means consisting of bulbs terminating said tubular portion whereby additional condensing surface is obtained for said vapor.

6. A mercury vapor apparatus comprising an exhausted container, suitable mercury electrodes therein and a light giving tubular portion thereof, together with means for adjusting the density of the mercury vapor therein during normal operation to the density corresponding to approximately 300 degrees centigrade.

7. A mercury vapor apparatus comprising an exhausted container, separated bodies of mercury therein operating as electrodes and a light giving portion of said container between said electrodes, together with means for adjusting the density of the mercury vapor in said container during normal operation to the density corresponding to 300 degrees centigrade approximately, said means consisting of portions of said container exposed to the mercury vapor outside said light giving portion, whereby said adjustment of the mercury vapor density is obtained.
